UNITED STATES PATENT OFFICE

2,248,856

BRIDGE INDICATOR

Armin J. Dieckmann, Saginaw, Mich.

Application June 21, 1939; Serial No. 280,383

2 Claims. (Cl. 116—131)

This invention relates to improvements in indicators for use in the playing of games, more especially in the playing of contract or auction bridge. In these particular games, especially in contract bridge, it is necessary to show the standing of the players so that the persons engaged in the game will be able to determine the manner of bidding and playing. Currently used devices for this purpose are not always satisfactory in most instances because the type of the table is encumbered in one way or another. The instant indicator provides a convenient arrangement which avoids encumbering the table top and which is so arranged as to readily suggest to the players the requirement of operating the indicator from time to time. With this preamble in mind the objects of the invention are as follows:

First, to provide an indicator which is of especial use in the playing of either contract or auction bridge, its particular value being to denote the numerical not vulnerable or numerical vulnerable standing of a player during the bidding and play.

Second, to provide an indicator of the foregoing kind which is easily and in most instances desirably embodied in a bridge table top so as to avoid getting in the way of the player and to be instantly accessible for use.

Third, to provide an indicator device wherein the indicator head is both revoluble and axially movable in respect to a window in the carrier of said device thereby to either display the peripheral numerals above or in combination with a colored signal band.

Fourth, to provide an indicator wherein the chief principle is that of a push and pull to denote the vulnerable or not vulnerable stage in the play, the peripheral numerals always being in view and common to both stages.

Other objects and advantages will appear in the following specification, reference being had to the accompanying drawing, in which:

Figure 1 is a cross section of a portion of a bridge table showing the indicator in place.

Figure 2 is a plan view of said portion of the table illustrating the relationship of the indicator to the window in the table top.

Figure 3 is a cross section taken on the line 3—3 of Fig. 1.

Figure 4 is a cross section taken on the line 4—4 of Fig. 1.

Figure 5 is a perspective view of the movable indicator device.

Figure 6 is a view similar to Fig. 1, illustrating

the modification of the indicator device to suit a thin table top.

Figure 7 is a partially plan and sectional view illustrating the embodiment of the indicator in the table ledge.

The indicator device, generally designated 1 in all forms of the invention, comprises a member which is adapted to be either pushed or pulled and turned in order to control the visibility of the indicia and signal bands 2, 3, through an opening 4 herein known as the window in a carrier 5. The indicator device 1 is capable of being made in any one of several ways.

In Fig. 1 said device comprises a cylindrical head 6 on the periphery of which the indicia and signal bands 2, 3, are applied contiguously to each other. The indicia band comprises a series of members 7 which extend circumferentially of the head 6, and may, if desired, be separated from each other by division lines 8 or some suitable equivalent thereof. Such divisions are, however, not essential, but the spacing is so arranged that a blank 9 is left between adjacent numbers, said blank denoting a neutral or starting point. The signal band 3 is usually red, but it may consist of some other color.

The material from which the cylindrical head 6 is composed is not essential to the invention. The substances from which it may commonly be made comprises wood, metal, plastic material or a combination of any of these materials. The head 6 is carried by a shaft 10. The head is affixed to the shaft a slight distance in from one end so as to define a trunnion 11 which has slideable and turnable support in a bearing 12. A similar bearing 13 supports the shaft 10 adjacently to its other end, said end being equipped with a finger-piece 14 by which the entire indicator device is capable of being turned or pushed and pulled.

Free motion in these respects is prevented by a spring clip 15 which acts as a brake (Fig. 4). Said spring bears up against the shaft, for which purpose it preferably has a curved terminal 16. The tension on the spring 15 is sufficiently great to hold the indicator device in any of its adjusted positions. Said clip, like the bearings 12, 13, is secured to the previously mentioned carrier 5 which in this embodiment comprises a table top. The opening 4 is usually glazed at 17, and the margin of the opening is beveled at 18 to prevent the cards from being caught against said opening. The periphery of the head 6 comes close to the glass insert 17, and for that purpose the nether

side of the table is recessed at 19 so as to admit a part of the head 6.

The end shoulders 20, 21, of the recess 19 provide stops for limiting the sliding motion of the indicator device. The indicia band 2 is broad enough so that the members 7 which are centered therein will always show through the window 4 whether the indicator device is in the full or dotted line positions (Fig. 1). When said device is in the full line position, the signal band 3 is covered by that portion of the carrier 5 between an edge of the window 4 and the shoulder 20. The numerals 7, however, show clearly. When the device is pulled to the dotted line position, wherein the head 6 is limited by the shoulder 21, the numerals still show, but the signal band 3 is now also revealed through the window, indicating that the two who are partners in the game are vulnerable.

It is observed in Fig. 1 that the table top 5 is much thicker than the corresponding table top in Fig. 6. For that reason the head 6 is made as a separate cylinder on the shaft 10, and sufficiently larger than the shaft to enable bringing the periphery of the cylinder up close to the window 4. In Fig. 6, which illustrates a thin table top, there is no necessity for making the shaft and head as separate parts. The indicia and signal bands 2, 3, are applied to one end of a uniformly sized cylinder 22, the other end 23 of which comprises the equivalent of the foregoing finger-piece 14. The window 4 is now a simple unglazed opening with beveled edges at 18.

A screw 24 is driven into the banded end of the cylinder 22. This screw is adjustable by turning it in or out with a screw driver so as to vary the distance of its head 25 in respect to a bracket 26 in which the shank of the screw has slidable and turning bearing. It is thus that one end of the indicator device is supported, the other end being held by a ledge 27 depending from the edge of the table.

Figure 7 illustrates a further modification wherein the indicator device 1 is embodied in the marginal ledge 28 of the table. This ledge is heavier in construction than the ledge 27 in Fig. 6. It is bored at 29 to slidably and turnably contain the indicator device. The bore is closed at 30 and its otherwise open end is partly capped by a metal corner-piece 31. Said corner-piece has an opening 32 in which the shaft 10 is slidably and turnable. Said shaft comprises the reduced extension of what is again termed a head 6, said head having indicia and signal bands 2, 3 as in Fig. 1.

It will be observed that the modification in Fig. 7 combines the principles of the modifications in Figs. 1 and 6. Although the indicator device 1 (Fig. 7) is much shorter than said device in Fig. 1, yet it preserves the distinction between the head 6 and shaft 10. The latter protrudes from the corner-piece 31 as does the cylinder 22 in respect to the ledge 27 in Fig. 6, thus providing a finger-piece 33 which is the equivalent of any of the finger-pieces 14, 23. The screw of Fig. 6 is now employed to act as an adjustable stop in respect to the bore end 30. Said screw is now designated 34.

The shoulder 35 at the juncture between the head 6 and shaft 10 is abuttable with that portion of the corner-piece 31 that carries the shaft, thus to limit the pulling motion of the indicator

device. The ledge 28 constitutes the carrier, and it has a window 4 as in the other modifications, through which the indicia and signal bands can be seen in the manner brought out above.

5 The operation has already been described in some detail, for which reason it is thought unnecessary to state more than to point out that in all modifications the indicator device operates on the principle of pushing and pulling, either 10 to reveal the signal band 3 in combination with the indicia band 2, or to conceal the signal band and leave only the indicia band open to view, at the same time providing for the turning of the indicator device, regardless of which of the 15 two positions it may be in. The indicator comprises the device 1 and the carrier 5, regardless of what the nature of the latter may be. It is herein shown as the top of a table, but it may 20 comprise some equivalent which has a window through which the indicia and signal bands can be viewed.

The carrier functions as a part of the combination because the shoulders which it has are used to limit the push and pull movements of 25 the indicator device. Moreover, a portion of the carrier is required to conceal at least one of the bands; the signal band 3 in this instance.

The card-table must be equipped with two of the indicators, one for the north and south players 30 who are partners, and one for the east and west players who also are partners. After a hand has been played, the one device is set at the points won by the two partners on their own indicator. After the next hand is dealt it is 35 not permitted to ask the score but it is permissible to look at the score and it is important that the score is known at all times, and if the score is kept as usual on a score pad it cannot be readily seen, while with this device it is easily 40 seen by all four players.

I claim:

1. An indicator comprising a table portion having a window and a recess defining a pair of end shoulders, an indicator device having a head partly occupying said recess but being 45 shorter than the recess, said head having contiguous indicia and signal bands adapted to be seen through said window, a shaft included in said device being of less size than the head, and bearings slidably and turnably attaching the shaft to the table portion and maintaining said head in the recess in registration with said end shoulders, thereby to limit the push and pull movements of said device by the engagements of the head with the respective shoulders.

2. An indicator comprising a table portion

having a window and a recess defining a pair of end shoulders, an indicator device having a head partly occupying said recess but being shorter than the recess, said head having contiguous indicia and signal bands adapted to be seen through said window, a shaft included in said device being of less size than the head, and bearings slidably and turnably attaching the shaft to the table portion and maintaining said head in the recess in registration with said end shoulders, thereby to limit the push and pull movements of said device by the engagements of the head with the respective shoulders.

3. An indicator comprising a table portion having a window and a recess defining a pair of end shoulders, an indicator device having a head partly occupying said recess but being shorter than the recess, said head having contiguous indicia and signal bands adapted to be seen through said window, a shaft included in said device being of less size than the head, and bearings slidably and turnably attaching the shaft to the table portion and maintaining said head in the recess in registration with said end shoulders, thereby to limit the push and pull movements of said device by the engagements of the head with the respective shoulders.

4. An indicator comprising a table portion having a window and a recess defining a pair of end shoulders, an indicator device having a head partly occupying said recess but being shorter than the recess, said head having contiguous indicia and signal bands adapted to be seen through said window, a shaft included in said device being of less size than the head, and bearings slidably and turnably attaching the shaft to the table portion and maintaining said head in the recess in registration with said end shoulders, thereby to limit the push and pull movements of said device by the engagements of the head with the respective shoulders, and brake means to restrict the free turning and pushing or pulling movements of the indicator device.
